REVERSIBLE HANGER MOUNTING FOR
PICTURES AND THE LIKECamillo Di Nuccio, Providence, R. I., assignor of
one-half to John Bevilacqua, Providence, R. I.

Application March 7, 1936, Serial No. 67,657

3 Claims. (Cl. 248—28)

My present invention relates to household hardware, and has particular reference to an improved construction for a reversible hanger mounting for pictures and the like.

- 5 It is the principal object of my invention to provide a novel picture hanger which may be used alternatively for hanging pictures on nails inserted in the walls, or for utilizing hanging cords or wire.
- 10 It is another object of my invention to provide a very simple construction which may be readily manufactured by means of a low cost operation, whereby the cost of manufacture is reduced, and the selling price is reasonable.
- 15 With the above and other objects and advantageous features in view, my invention consists of a novel arrangement of parts more fully disclosed in the detailed description following, in conjunction with the accompanying drawing, and more specifically defined in the claims appended thereto.

In the drawing:

Fig. 1 is a perspective view of the back of a picture frame, showing the novel hanger in operating position;

Fig. 2 is a perspective view of the novel hanger;

Fig. 3 is a sectional view showing how the novel hanger is utilized with wall nails or the like; and

30 Fig. 4 is a perspective view showing how the novel hanger is used with cords or wires.

Referring to the drawing, the picture frame 10 has a novel hanger 11 mounted thereon, the novel hanger 11 being shown in enlarged detail in Fig. 2, and comprising a strip of sheet metal bent, preferably by a stamping operation, in the form illustrated so as to provide a back 12, sides 13, and laterally positioned ends 14, the ends being provided with screw or nail openings 15 centrally located and with centering and locking prongs 16 which are preferably struck from the material itself. The back 12 is cut out as disclosed, with a V-cut or slot 17 at one end and two arms 18 inclined as illustrated to form a guideway and having sufficient resilience to give when forced over a nail shank, as hereinafter disclosed, the arms 18 being spaced from the body of the back to provide aligned recesses 19.

When the improved hanger is mounted on the back of a picture frame with the V slot 17 in upward position, the novel hanger is suitable for use with nails, screws and other picture hanging devices of similar nature, the shank 20 of the nail 21 entering between the arms 18 to be guided towards the V slot and shifting

said arms laterally against their resilience to permit entrance of the shank into the V slot, whereby the picture becomes centrally positioned; the head 22 of the nail is positioned in the space between the V slot and the upper ends 5 of the arms, the available opening being designed to be smaller than the width of the head 22, whereby it is impossible to remove the hanger from the nail, and therefore the picture from the wall, unless intentionally done by thrusting upwardly. An upward thrust causes the shank 20 to enter between the curved ends 23 of the arms 18 and to thrust them aside so as to permit removal of the hanger from the nail. My improved construction therefore provides a very 10 simple arrangement, easily attached to the back of a picture or the like, and adapted to be securely locked in place on the shank of a nail or any similar fastening, the removal being easily effected if desired.

The position of the resilient arms 18, which are spaced from the body of the back to provide recesses 19, permits an alternative use of the novel picture hanger in that the mounting on the back of the frame may be reversed, whereby the recesses 19 are upwardly positioned and a cord or wire loop 24 may be readily locked to the hanger by first inserting the wire loop inwardly between the arms 18 and then passing the sides of the loop outwardly into the recesses 30 19, as indicated in Fig. 4. My improved invention therefore may be used for hanging pictures on nails and the like or may be used in conjunction with supporting wires and cords as preferred.

While I have described a specific constructional embodiment of my invention, made of stamped sheet material, and therefore adapted for manufacture and sale at a low price, it is obvious that changes in the details of construction, in the material used, and in the arrangement of the cooperating parts, may be made to suit the requirements for different hanger needs without departing from the spirit and the scope of the invention as defined in the appended 40 45 claims.

I claim:

1. In a picture hanger device, a plate having a nail shank receiving opening, the lower portion of the plate having two resilient arms extending 50 upwardly from the edge thereof with their adjacent edges angularly disposed with relation to each other to provide a guide passage for a nail shank, the edge of said opening opposite the guide passage being formed as a seat, the upper 55

portions of said arms normally closing said shank receiving opening to a nail shank but being movable by pressure of a nail shank on said adjacent edges to permit movement of the nail shank past said upper portions and into said opening for positioning in said seat.

2. In a picture hanger device, a plate having a nail shank receiving opening, the lower portion of the plate having two resilient arms extending upwardly from the edge thereof with their adjacent edges angularly disposed with relation to each other to provide a guide passage for a nail shank, the edge of said opening opposite the guide passage being formed as a seat, the upper portions of said arms normally closing said shank receiving opening to a nail shank but being movable by pressure of a nail shank on said adjacent edges to permit movement of the nail shank past said upper portions and into said opening for positioning in said seat, re-

cesses being formed between said arms and the sides of the plate and communicating with said opening.

3. In a picture hanger device, a channel shaped member having a plate, two side edges, and two ends parallel to said plate whereby said plate is spaced from the plane of said ends, said plate having an opening, the lower portion of the plate having two resilient arms extending upwardly from the edge thereof with their adjacent edges angularly disposed with relation to each other to provide a guide passage, the upper portions of said arms normally closing said opening to entrance of a wire or the like from the guide passage, but being movable to permit passage of a wire or the like past said upper portions and into said opening, recesses being formed between said arms and the sides of the plate and communicating with said opening.

CAMILLO DI NUCCIO.
